UNITED STATES PATENT OFFICE.

THOMAS M. ANDREWS, OF NASHVILLE, TENNESSEE, ASSIGNOR OF ONE FOURTH TO JOHN A. GAINES AND WORCESTER A. BRYAN, OF NASHVILLE, TENNESSEE.

ROTARY ENGINE.

SPECIFICATION forming part of Letters Patent No. 732,671, dated June 30, 1903.

Application filed December 26, 1901. Serial No. 87,264. (No model.)

To all whom it may concern:

Be it known that I, THOMAS M. ANDREWS, a citizen of the United States, residing at Nashville, in the county of Davidson, State of Tennessee, have invented certain new and useful Improvements in Rotary Engines, of which the following is a description, reference being had to the accompanying drawings and to the characters of reference marked thereon.

- 10 My invention relates to steam-engines of the rotary type; and it is the object of my invention to simplify the construction of such engines, to construct an engine in which the steam shall be used to the fullest advantage
 15 possible, to obviate the knocking common in engines of this type caused by the impact of the steam upon the wing-piston, and to reduce the friction and leakage of steam as much as possible.
 20 With these objects in view my invention consists in the construction hereinafter described and claimed.

Referring to the drawings, Figure 1 is a vertical cross-sectional view of an engine embodying my invention on a plane at right angles with the axis of the shaft. Fig. 2 is a vertical cross-sectional view on a plane parallel with the axis of the shaft. Fig. 3 is a plan view of the packing-disk. Fig. 4 is a view, partly in section, of one of the piston-wings. Fig. 5 is an end view of one of the piston-wings. Fig. 6 is a detail view showing a portion of the piston-disk in cross-section, and Figs. 7 and 8 are respectively a plan 35 and a cross-sectional view of one of the heads of the casing.

In the drawings, 1 is a cylindrical casing having heads 2. A power-shaft 3 is carried in bearings 4, arranged above the center of 40 the heads 2. Within the casing, secured to the power-shaft and concentric therewith, is a piston-disk 5, having oppositely-extended openings 6, in which are carried piston-wings 7 and 8. The piston-disk 5 is of such diameter and the bearings 4 are so located relative to the center of the casing that at one point, preferably at the point directly above the center of the casing, the piston-disk is in contact with the inner periphery of the casing. The 45 openings 6, in which the piston-wings are car-

ried, are arranged diametrically opposite each other. In the face of the piston-disk are formed the oppositely-located eccentric grooves 9 and 10. These grooves are so located that they have their greatest depth at 55 points immediately between the openings 6 and taper in both directions from these points.

The wings 7 and 8 are each provided, preferably on each side near their inner ends, with pins 11, which carry curved guides 12, 60 which travel in grooves 13, formed in the inner faces of the heads 2, concentric with the inner periphery of the casing, but eccentric to the bearings 4.

The inner ends of the piston-wings 7 and 8 65 are preferably V-shaped, as shown in Figs. 2 and 4, and the inner ends of the openings 6 are formed with a central rib 14, which fits this V-shaped groove, and thus prevents the piston-wings from possible lateral movement 70 when the piston-disk is in contact with the inner periphery of the casing, and thus tends to lessen the friction between the disks 24 and the walls of the casing at this point.

The outer ends of the piston-wings 7 and 8 75 travel in contact with the inner periphery of the casing and for the purpose of making a tight joint are preferably provided with packing 15, pressed outward by a spring 17, preferably carried in a recess 18 in a seat-piece 80 19. The end walls 20 of this recess prevent lateral movement of the spring. The side edges of the piston-wings are preferably also provided with packing 21, carried in grooves 22, and preferably pressed outward against 85 the inner faces of the heads 2 by springs 23.

From the above description it will be seen that the piston-wings in the rotation of the shaft and the piston-disk are always in contact with the inner periphery of the casing. 90

On each face of the piston-disk 5 and concentric therewith is preferably arranged a disk 24, having slots 25 therein, through which the pins 11 of the piston-wings extend to connect with the guides 12 in the grooves 13. 95 These disks each fit into a circular recess 26, formed in the inner face of each of the heads 2. At the periphery of these recesses is provided a groove 27, in which is placed packing 28. By this construction the possibility of 100

leakage of steam at the bearings 4 is obviated without the necessity for packing at these bearings.

At the point at which the periphery of the piston-disk is in direct contact with the inner periphery of the casing I provide packing 29, preferably pressed by springs 30 into close contact with the periphery of the piston-disk, and at this point I also provide a valve-carrier 31, having its inner end adapted to fit the eccentric grooves 9 and 10. This end of the valve-carrier is preferably provided with packing 32 in order to insure a tight joint with these grooves.

15 The valve-chamber 33 is preferably formed in one piece with the casing 1. Connected with it is the steam-inlet 34 and the exhaust-openings 35 and 36. The steam-inlet 34 extends downward into the valve-chamber and 20 has at its lower end a valve-seat 37, adapted to receive the valve 38, carried by the valve-carrier 31.

From the valve-chamber 33 steam-inlets 39 and 40 extend to the interior of the casing, 25 and each of these inlets is adapted, by means of connections 41 and 42, to act, as hereinafter described, as exhaust-outlets.

Communicating with the valve-chamber 33 are also exhaust-outlets 43 and 44, formed 30 in the walls of the casing and opening into the casing at diametrically opposite points equally distant from the point at which the valve-carrier 31 is located.

A valve-rod 45, operated by any convenient 35 means, preferably by a lever 46, carries within the valve-chamber 33 valves 47 and 48, each provided with a way 49 and each adapted when in one position to open the exhaust-outlet 43 or 44 and to connect the inlet 39 or 40 with the exhaust and at the same time close the inlet 39 or 40 and when shifted in position to close the exhaust-outlet and to open the inlet 39 or 40. In the position in which the valves 47 and 48 are shown in Fig. 45 1 the valve 47 has opened the outlet 43, and also by means of the way 49 and the connection 41 has connected the inlet 39 with the exhaust and the valve 48 has closed the exhaust 44 and has opened the inlet 40.

50 The parts being in the position shown in Fig. 1, the valve-carrier resting at the bottom of the groove at its greatest depth and the valve 38 being at a distance from its seat, steam enters the casing through the inlet 40 55 and entering the groove 9 acts to force the piston-wing 7 downward, escape of steam in the opposite direction being prevented by the valve-carrier 31. As soon as the piston-disk is rotated sufficiently to carry the piston-wing

60 8 past the opening of the outlet 43 there will be no resistance within the casing to the further movement of the piston-wing 7, any steam which fails to escape before the piston-wing 8 passes the opening of the outlet 43 having 65 free exit through the inlet 39, connection 41, and way 49. As the piston-disk continues to rotate the valve-carrier 31 will be gradually

raised, cutting off the supply of steam. When the piston-wing 7 has reached about the point marked *a* in Fig. 1, the valve-carrier will be raised to its fullest extent, completely shutting off the steam. From this point the steam already introduced in rear of the piston-wing 7 acts by its expansion to drive the piston-wing 7 forward to the point marked *b*. The piston-wing 8 having passed the mouth of the exhaust-outlet 43, there will be no back pressure on the piston-wing 7. As the piston-disk continues to rotate the piston-wing 8 approaches the highest point 80 of the interior periphery of the casing, the valve-carrier being still raised, holding the valve 38 against its seat, and thus preventing the entrance of steam to the valve-chamber. As the piston-wing 7 reaches about the point marked *b* in Fig. 1 the piston-wing 8 having passed the valve-carrier and the valve-carrier having entered the groove 10, permitting the valve 38 to be forced away from its seat, steam enters in rear of the piston-wing 8. At the instant steam enters and until the piston-wing 7 reaches the opening of the exhaust-outlet the pressure of the steam on the rear face of the piston-wing 8 is to a slight extent resisted by back pressure of the steam confined between the rear face of the piston-wing 7 and the front face of the piston-wing 8. At the moment steam enters in rear of the piston-wing 8 the area presented by it between the periphery of the piston-disk and the inner face of the periphery of the casing is about one-fourth the area presented by the rear face of the piston-wing 7. Consequently the back pressure on the piston-wing 8 will be sufficient only to have a cushioning effect to prevent the shock or jar which might otherwise occur from the entrance of the steam, this shock or jar being, however, very slight by reason of the gradual entrance of steam due to the gradual opening of the steam-inlet. It will thus be seen that the steam is introduced gradually and cut off gradually, and during a considerable portion of the rotation of the piston-disk the steam acts by its expansion, so that the full force of the steam is utilized.

The valve-carrier 31 is held down in contact with the grooves 9 and 10 by the pressure of the steam and is lifted against this pressure by the rotation of the piston-disk, 120 automatically cutting off the steam at points determined by the grooves.

It will be understood that the curve of the bottom of the grooves 9 and 10 may be varied to effect the cutting off of the steam at the points found most desirable.

I have described the operation of the engine when the valves 47 and 48 are in the position shown in Fig. 1. With the valves in this position the exhaust-outlet 44 is closed and has 130 no other function than that of affording additional space to hold steam. By shifting the valves 47 and 48 by means of the lever 46 the engine will be reversed, steam entering

through the inlet 39 and the exhaust-outlet 44 being open for the escape of the steam after it has done its work.

It will be understood that I do not limit my invention to the precise construction shown, as many changes in specific construction may be made without departing from the spirit of the invention. For instance, the valve-chamber and the steam-inlets may be arranged at the bottom or the side instead of the top of the casing, so long as the relative position of the inlets and exhaust-openings are preserved, and any known form of valve may be substituted for the sliding valves shown.

15 The difficulty of starting the engine, due to the fact that so long as the valve 38 is held in close position no steam can be admitted to act upon the piston-wings, may be readily obviated by coupling two engines of the construction shown on the same shaft with the piston-wings of one engine at such an angle with the piston-wings of the other that one or the other of the engines will always be in position to admit steam to act on its piston-wings. In a single engine this difficulty may be obviated by connecting the steam-chamber, by means of suitable connections, with one of the exhaust-outlets 43 or 44, so that steam may by means of these connections be admitted directly to the steam-space in the casing.

35 The valve-carrier 31 is shown square in cross-section; but it will be obvious that it may be made of any form in cross-section desired.

It will be obvious that instead of steam any other gaseous motive fluid may be used.

Having thus described my invention, what I claim, and desire to secure by Letters Patent, is—

40 1. A rotary engine comprising a casing having an exhaust-port communicating with the interior of the casing at a point on about the level of the center of the casing, and having an inlet-port in its upper portion, a piston-disk eccentrically mounted in the casing and carrying oppositely-arranged piston-wings, a cut-off valve and means for operating it directly by the piston-disk; substantially as described.

45 2. A rotary engine comprising a casing, a piston-disk eccentrically mounted in the casing and carrying two oppositely-arranged piston-wings, a valve-chamber connected with the casing by an inlet-port, an exhaust-port opening from the casing, means for admitting steam to the valve-chamber and a cut-off valve operated directly by the piston-disk for automatically cutting off the supply of steam to the valve-chamber before the piston-disk has completed a half-rotation; substantially as described.

50 3. A rotary engine comprising a casing having an exhaust-port communicating with the interior of the casing at a point on about the level of the center of the casing and having an inlet-port in its upper portion, a piston-

disk eccentrically mounted in the casing and carrying oppositely-arranged piston-wings, means for maintaining the outer ends of the piston-wings in contact with the inner periphery of the casing, a cut-off valve and means for operating it directly by the piston-disk; substantially as described.

55 4. A rotary engine comprising a casing, a piston-disk rotating therein carrying two oppositely-arranged piston-wings and having a cam-groove in its periphery, a valve-chamber connected with the casing by an inlet-port, an exhaust-port opening from the casing, means for admitting steam to the valve-chamber and means operated by the cam-groove of the piston-disk for automatically cutting off the supply of steam to the valve-chamber before the piston-disk has completed a half-rotation; substantially as described.

60 5. A rotary engine comprising a casing having an exhaust-port communicating with the interior of the casing at a point on about the level of the center of the casing, and having an inlet-port in its upper portion, a piston-disk eccentrically mounted in the casing and carrying oppositely-arranged piston-wings and having a cam-groove in its periphery and a cut-off valve operated directly by the cam-groove of the piston-disk; substantially as described.

65 6. A rotary engine comprising a casing having an exhaust-port communicating with the interior of the casing at a point on about the level of the center of the casing and having an inlet-port in its upper portion, a piston-disk eccentrically mounted in the casing and carrying oppositely-arranged piston-wings and having cam-grooves in its periphery, means for maintaining the outer ends of the piston-wings in contact with the inner periphery of the casing, and a cut-off valve operated directly by the cam-grooves of the piston-disk; substantially as described.

70 7. A rotary engine comprising a casing having an exhaust-port communicating with the interior of the casing at a point on about the level of the center of the casing, a valve-chamber connected with the casing by an inlet-opening, an inlet for admitting steam to the valve-chamber, a piston-disk eccentrically mounted in the casing and carrying oppositely-arranged piston-wings, a cut-off valve arranged in line with the inlet for admitting steam to the valve-chamber and operating against the force of the steam, and means for operating the valve directly by the piston-disk; substantially as described.

75 8. A rotary engine comprising a casing having an exhaust-port communicating with the interior of the casing at a point on about the level of the center of the casing, a valve-chamber connected with the casing by an inlet-opening into the casing at its upper portion, an inlet admitting steam to the valve-chamber, a piston-disk eccentrically mounted in the casing and carrying oppositely-arranged piston-wings, means for maintaining

the outer ends of the piston-wings in contact with the inner periphery of the casing, a cut-off valve arranged in line with the inlet for admitting steam to the valve-chamber and 5 operating against the force of the steam, and means for operating the valve directly by the piston-disk; substantially as described.

9. A rotary engine, comprising a casing, an inlet for admitting steam to the casing, an exhaust-port and a piston-disk carrying oppositely-arranged piston-wings, the inner ends of the piston-wings being made V-shaped and the piston-disk being provided with a rib to fit the V-shaped inner ends of the piston-wings whereby the piston-wings are centered when in contact with the rib; substantially as described.

10. A rotary engine, comprising a casing having heads provided with a circular recess 20 formed therein, an inlet for admitting steam to the casing, an exhaust-port, a piston-disk arranged within the casing and carrying oppositely-arranged piston-wings and radially-slotted disks fitting the recess formed in the 25 heads and arranged between the piston-disk and the heads, the piston-wings being provided with pins extending through the slots of the disks; substantially as described.

11. A rotary engine, comprising a casing 30 having heads provided with a circular recess formed therein, having at its periphery a recess for packing, an inlet for admitting steam to the casing, an exhaust-port, a piston-disk arranged within the casing and carrying op-

positely-arranged piston-wings, and radially-slotted disks fitting the recesses formed in the heads and arranged between the piston-disk and the heads, piston-wings being provided with pins extending through the slots of the disks; substantially as described. 35

12. A rotary engine, comprising a casing and casing-heads, the latter having annular grooves eccentrically disposed to the movement of the piston-disk, a piston-disk revolvably carried in the casing, having a series of 40 radial pockets, with tapered seat portions, a series of piston-wings movable in said pockets having cut-out portions adapted to the tapered seat portions of the pockets and provided with studded projections carrying rollers movable in the aforesaid grooves for shifting the wings, as and for the purpose described. 45

13. In a device of the class described, a rotary piston-disk having a series of tapered 50 body portions, wings slideable in ways of said piston-disk and provided with seat portions adapted to the tapered body portions of the piston-disk, and the said wings having their bodies recessed and packed with suitable 55 packing, substantially for the purpose described.

In testimony whereof I affix my signature in presence of two witnesses.
